COMBINED MONEY CLIP AND CHANGE PURSE

Alexander K. Sapiro, Los Angeles, Calif.

Application July 16, 1959, Serial No. 56,799

Term of patent 14 years

(Cl. D87—3)

FIG 1

I claim:

The ornamental design for a combined money clip and change purse, substantially as shown.
